INVENTOR.

George Bohon Schmitt,

BY

Geo. Schmitt ATTORNEY.

UNITED STATES PATENT OFFICE.

GEORGE BOHON SCHMITT, OF NEWARK, OHIO.

FOLDABLE TABLE.

Application filed July 20, 1927. Serial No. 207,148.

This invention relates to folding tables, and has for its object to provide, in a manner as hereinafter set forth, a table of such class capable of being folded in a compact manner when not desired for use and conveniently extended for use and expeditiously latched in extended position.

Further objects of the invention are to provide, in a manner as hereinafter set forth, a folding table which is simple in its construction and arrangement, strong, durable, compact, thoroughly efficient in its use, readily extended and folded, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an inverted plan view of the table when extended and with the top thereof, which is formed of a pair of sections, in non-latched position.

Figure 2 is a cross sectional view of the table and with the top thereof in latched position.

Figure 3 is a view similar to Figure 2 taken at right angles to the latter.

Figure 4 is an elevation of the supporting section of the table in folded position.

Figure 5 is an elevation of the sectional table top in folded position.

Figure 6 is a fragmentary view in plan of the supporting section of the table extended and illustrating a latch therefor.

Figure 7 is a fragmentary view in elevation of the supporting section of the table illustrating a retaining bar connected therewith for maintaining articles stacked on the supporting section of the table.

Referring to the drawings in detail the foldable table includes a foldable supporting section comprising a body portion consisting of four oblong body members 1, 2, 3 and 4 hinged together at their ends and each of which is of the same length and same width.

The body members are disposed at right angles with respect to each other and are arranged in pairs, one pair formed by the body members 1, 3 and the other pair formed by the body members 2, 4. One end of the body member 1 abuts against the inner face of the body member 3 at a point slightly removed from an end of the latter and one end of a body member 4 abuts against the inner face of the body member 2 at a point slightly removed from one end of the latter. One end of the members 1 and 4 abut against the inner faces of the members 3 and 2 respectively, in proximity to an end of said members 3 and 2 when the body portion is extended in the manner as illustrated in Figure 1. One end of the body member 2 is spaced from one end of the body member 1 and one end of the body member 4 is spaced from one end of the body member 3 and the said members are hinged together in a manner to provide for the spacing arrangement just referred to. Four hinge elements are employed for connecting the body members together and each hinge element consists of a pair of straps 5, 6 pivoted together as at 7. The strap 5 is of greater length than the strap 6. The hinge elements are referred to generally by the reference characters 8, 9, 10 and 11. The short straps 6 of the elements 8 and 9 are fixedly secured to the inner face of the body member 1 and the elongated straps 5 of the elements 8, 9 are fixedly secured to the inner face of the body members 2, 3, respectively. The short straps 6 of the elements 10, 11 are secured to the inner face of the body member 4 and the elongated straps 5 of the elements 10, 11 are secured to the inner faces of the body members 2, 3, respectively. The element 8 spaces the body member 2 from the body member 1 and the element 11 spaces the body member 3 from the body member 4. The arrangement of the elements 8, 9, 10 and 11 in the manner as stated provides for the folding of the body portion in the manner as shown in Figure 4 and further for the extending of the body portion in the manner as shown in Figure 1.

For latching the body portion extended, as shown in Figure 1, the body member 3 in proximity to one end thereof is provided with a pair of superposed, laterally extending eyes 12, see Figures 6 and 7, adapted to extend through a hinged plate 13 provided with

a pair of openings 14. The plate 13 is pivotally connected as at 15' to a plate which abuts against one end of the body member 3 and is fixedly secured in proximity to the upper end 5 of a supporting leg to be presently referred to.

The supporting section further includes two pairs of supporting legs. The legs of one pair are indicated at 15, 16 and the legs of the other pair at 16, 18. The legs of each 10 pair are connected, together, in proximity to their lower ends, by a brace member 19. Each of the legs of each of said pairs is mortised, as at 20, at the upper portion thereof to provide a seat 21. The mortise is of 15 the same height as the body member. The body member 1 is mounted upon the seats formed on the legs 15, 16 and the body member 4 is mounted on the seats 21 formed in the supporting legs 17, 18. The body member 2 20 abuts against the supporting leg 17 and the body member 3 abuts against the supporting leg 16. The plate, in which the plate 13 is hinged, is indicated at 22 and which is secured to the supporting leg 16.

25 When the body portion is extended and with the supporting legs arranged in the position shown in Figure 1, the plate 13 is shifted against the body member 3, whereby the eyes 12 will extend through the openings or slots 30 14 and any suitable means can be passed through the eyes for the purpose of latching the body portion in extended position.

The table top can be of any suitable contour, and by way of example is shown square, 35 and it is formed of two sections 23, 24 each provided with a pair of strips 25, 26 secured to the lower face thereof. Each pair of strips is hinged together as at 27, and by this arrangement the top can be folded if desired.

40 When the top is extended the strips of each pair abut and the combined length of each pair of strips is such as to extend from the body member 2 to the body member 3 and under such conditions setting up a snug fit 45 when the extended top is mounted upon the supporting sections as shown in Figures 1, 2 and 3. A latch 28 is employed for detachably connecting the sections of the top together when extended. The top is of an area 50 materially greater than the area of the body portion when the latter is extended. The top is removably mounted upon the body portion of the supporting sections when the latter are extended.

55 Each supporting leg is provided at its top with an outwardly extending loop 28', for the reception of a vertically disposed rod or retaining means adapted for maintaining articles stacked upon the supporting section, 60 when the table top is not employed.

It is thought the many advantages of a foldable table, in accordance with this invention, can be readily understood, and although the preferred embodiment of the invention is as 65 illustrated and described, yet it is to be un-

derstood that changes in the details of construction can be had which will fall within the scope of the invention as claimed.

What I claim is:

1. A foldable table comprising a body portion formed of two pairs of body members spaced from each other, the body members of each pair disposed at right angles from each other and hinged together, one of the body members of each pair having one end 70 abutting against the inner face of the other body member of the pair and means for hinging one pair of body members to the other pair and for maintaining them in spaced relation, a pair of supporting legs secured to the ends of a body member of each pair, and means carried by the upper end of one of said legs and detachably connecting with one of said body members for latching said pairs of body members together for maintaining 75 said body portion in extended position.

2. A foldable table comprising a body portion formed of two pairs of body members spaced from each other, the body members of each pair disposed at right angles from each other and hinged together, one of the body members of each pair having one end 90 abutting against the inner face of the other body member of the pair and means for hinging one pair of body members to the other pair and for maintaining them in spaced relation, a pair of supporting legs secured to the ends of a body member of each pair, and means carried by the upper end of one of said legs and detachably connecting with one of said 95 body members for latching said pairs of body members together for maintaining said body portion in extended position, and a sectional hinged top having means on its inner face for abutting the inner faces of the body members when the top is mounted on the body portion and extended.

3. A foldable table comprising a body portion formed of two pairs of body members spaced from each other, the body members 100 of each pair disposed at right angles to each other and hinged together, means for hinging one pair of body members to the other pair and for maintaining one pair of body members spaced from the other pair, a pair of 105 supporting legs secured to one of the body members of each of said pairs, and means carried by the upper end of one of said legs and connected with one of the body members for latching said pairs of body members 110 together to maintain said body portion in extended position.

4. A foldable table comprising a body portion formed of two pairs of body members spaced from each other, the body members 115 of each pair disposed at right angles to each other and hinged together, means for hinging one pair of body members to the other pair and for maintaining one pair of body members spaced from the other pair, a pair of 120

supporting legs secured to one of the body members of each of said pairs, means carried by the upper end of one of said legs and connected with one of the body members for latching said pairs of body members together to maintain said body portion in extended position, and a sectional hinged top

having means on its inner face abutting against the inner face of said body portion when the top is mounted on the body portion and extended to maintain the top in position.

In testimony whereof, I affix my signature hereto.

GEORGE BOHON SCHMITT.
